COWL

Edward Sokolik, New Brighton, Minn.

Application August 15, 1946, Serial No. 690,742

4 Claims. (Cl. 98—78)

11

This invention relates to cowls and particularly to a cowl without any moving parts, which has easily demountable parts, which has a type of cross-sectional construction that may be adapted to any shape, and which provides a finished terminus for any chimney or stack.

Cowls have been variously devised, to induce draft for exhausting smoke and providing ventilation. Some have a revolving member adjusting itself, so that its opening is on the leeward side. Others have a member, that twirls, and is shaped to direct air currents upward. Others, that have no moving parts, have either quite involved and expensive construction; or difficulty is experienced in maintaining draft on certain days, due to conflict of air currents, sometimes causing down draft. To provide power driven exhaust devices, is quite expensive. Constructions in general are difficult to mount; are in the form of an adjunct, which does not provide a finished appearance as part of the chimney; and do not have a typical vertical cross-sectional construction, that is applicable to any chimney shape. There is need for an effectual, though economically produced cowl, without any moving parts; which, by the joining of its parts, is readily demountable for inspection of flue, which has a construction, that will lend itself to any shape of horizontal chimney cross-section, whether curved or straight; and that will provide an ornamental chimney top.

An important object of my invention is to provide a cowl of such parts, that it is readily mounted on a chimney with the parts secured to each other and to the chimney, and that such parts which must be removed for inspection and cleaning are easily removed.

Another important object is to provide a cowl with such a type of vertical cross-sectional construction; that latitude is afforded to fit any horizontal chimney cross section, whether curved, straight sided or a combination of both.

Another object is to provide a cowl, that may be mounted on a steel stack as well as a chimney, by providing ports near the top of the stack and same serving as a part of the cowl.

Another object is to provide a cowl, that will give an ornamental and finished appearance to a chimney or stack, and not appear as an adjunct thereto.

Another object is to provide a cowl, that is economical to manufacture and is durable, requiring practically no maintenance or attention.

Other objects will be appa-
scription and appended claims.

For a full disclosure of my invention, reference is made to the description following and to the drawings, in which—

Fig. 1 is a side elevation view of my cowl, applied to a brick chimney with a part sectional view showing a port.

Fig. 2 is a vertical sectional view of same with a part section of the deflector in place.

Fig. 3 is a transverse sectional view on line 3—3 of Fig. 1.

Fig. 5 is a side elevation view of the flue show-

Fig. 6 is an end elevation view of the flue showing

Fig. 7 is a plan view of the cap as indicated by the line 7—7 of Fig. 2.

Fig. 8 is a transverse sectional view of the flue taken on the line 8—8 of Fig. 2.

Fig. 9 is an elevation view of the concave side of one of the two deflector plates.

In the selected embodiment of my invention, the top view of the same is shown in Fig. 10.

which is hereby disclosed, the numeral 12 represents the owl in its entirety. It is preferably

resents the cowl in its entirety. It is preferably made of sheet metal, but is not so limited, as it might be made of an asbestos composition board or other similar material. A flue 13 is provided in accordance with the shape of the chimney. This can be polygonal or curved or a combination of the two, as indicated at 14, and is provided

of both. In a steel stack, the stack itself provides the flue and through which ports may be provided. As shown in the drawings, the flue is of rectangular cross-section and ports 14 are provided in each of the four sides. These ports are provided to register with the inner ends of funnels 15, provided in the casing. Serrations 16

are provided on the bottom end 17 of the flue. These serrations extend outwardly at right angles, and provide support for the flue 13 on the top of the ceramic flue 18. The points of the serrations are easily clipped off to fit inside of the chimney wall 19. If necessary, a layer of packing is placed on the serrations 16 to seal same, for placing cementing material between the chimney wall 19 and the flue 13.

A demountable casing 20 closely fits over and encompasses the flue 13. By means of vertical division plates 21, the casing is divided, forming the air passages 15. These plates, in the form shown on the drawing, are preferably provided at the mid-point on each side and also extending diagonally inward from each corner. This

provides for interception of air currents impinging on the casing from any angle and inducing an increased draft, as will be subsequently explained. The casing 20 has a base portion 22, which provides a flat support for the casing on the structure of a flue, chimney or stack, and the top portion of this base provides a bottom lining for each of said air passages 15. This base may be formed in sections, with inturned flanges 23 and riveted, as indicated at 24, to division plates 21, or in other ways attaining an equivalent result. In similar manner, a top portion 25 of the casing 20 is formed. This is provided with a vertical flange 26 at the top thereof, in which holes are provided in registry with holes provided in the flue 13, for bolting together of the casing and flue. This also provides for a further attachment of a cap, as will be subsequently explained. Inturned flanges 27, similar to flanges 23, are provided and riveted, as indicated at 24, to division plates 21. It will be noted that the top portion 25 is shaped to provide a top lining for each of the air passages 15, and this lining is so arranged that a depending angle of same is in registry vertically with the lower edge of the ports 14. This forms a shield against direct horizontal flow of air into said ports, and which would have a turbulent effect on the draft. The construction provides for a maximum external opening of air passages to intercept all the air possible, and to deflect and converge same into the ports 14, passing through the ports in such an upward inclined angle that a suction is produced in the flue, resulting in a much accelerated draft upward. The roof 28 of the casing is preferably provided with a slight pitch. Beaded edges 29 are preferably provided on all outwardly projecting edges for stiffness and better appearance. It will be particularly noted, that the same cross-sectional construction through the side of the casing is applicable, whether the flue is square, round, rectangular, elliptical or any polygonal shape. The sections for the top and bottom of the air passages work naturally with the division plates to attain the desired shape. A division plate is employed at each corner or contour changing point, and such intermediate plates as are required for interception of air currents.

A cap 30, which is preferably of a shape to correspond to that of the roof 28 of the casing, is mounted on an open frame support 31 by bolts 32. The open frame support permits air currents to enter from any direction, and expedite emission of draft, originating in the flue and accelerated by air currents through the passages 15. Bolting, as indicated at 33, and as previously referred to, provides for a joining together of the cap 30, casing 28 and flue 13. It is apparent that the cap and casing are readily demountable from the flue. This facilitates greatly in cleaning and inspection of flues, as well as mounting of cowl in the first instance. It is of course only necessary to remove the cap to gain access to the flue. The assembly is supported by the base portion 22 on top of the chimney and by the cementing of the flue 13 into the chimney, after adjusting fit of the flue 13 into the chimney by clipping tips of the outwardly extending serrations 16. Whether the assembly is applied to an existing chimney or built into it during construction, the same result of a good appearing, well proportioned, finished chimney top is attained. It becomes a part of the chimney construction and does not have the appearance of

an adjunct thereto. Any unitary cowl is difficult to place and does not permit of such good fitting to the flue and top of the chimney. It is apparent that an assembly of proper shape and size may be fitted into and supported on a steel stack, with a neat appearance, and will function efficiently by providing ports like ports 14 of proper height and elevation.

To make certain that cross currents will not prevail through the ports 14, although same are shielded by depending angles of portion 25, I provide a deflector 34. This comprises two curved sheet metal plates 35, each of which have a pair of slits 36 in the mid-section thereof, permitting a portion of the plate to be formed into a loop 37 on the inner side thereof. A piece of spring metal 38, formed to the contour of the plates 35, is provided on the inner side thereof, and extending through said loop 37 of each of the plates. The pieces 38 are substantially co-extensive with said plates. A bolt 39, provided with a nut, extends through the loops of the two plates and through the pieces 38 holding same together securely. It will be apparent that the yieldable elements of such a deflector, permit its insertion into a flue at the desired elevation, and that it may readily be removed for cleaning and inspection of the flue. It is also apparent that this form of deflector, with change of size, will fit any shape of flue whether square, round, rectangular, elliptical or any regular polygon. As shown on the drawing, each port is segregated from the others, so there is no conflict of cross currents. The outside air, entering the ports after being accelerated through the air passages 15 and directed upward thereby, greatly boosts the draft in the chimney.

From the foregoing, the functioning of the cowl should be apparent. Air currents from any angle are intercepted by the vertical division plates, which are directed upwardly by the inclined portion of air passages, producing an upward suction and an accelerated draft in the flue. At the same time, any conflict of air currents is prevented by the deflector in the flue and the depending angle portion of the air passages. Further, the cap provides for drafting out horizontally and fends off any action to cause a down draft. The advantages of demountability and the versatility of the structure, in applying it to different shapes, have been previously stated.

While I have shown and described a preferred form of my invention, it is obvious that many changes, which are within the scope of my invention, will be apparent to those skilled in the art. I therefore desire to be limited only by the scope of the appended claims.

What I claim is:

1. A cowl comprising a tubular member, a demountable casing fitting over and encompassing said tubular member, a demountable cap engaging top of both said tubular member and said casing; said tubular member being adapted to fit within the upper portion of a flue, having means for adjustment to closely fit said flue and having a plurality of ports to allow flow of air into said tubular member above said flue; said demountable casing consisting of a plurality of vertical division plates extending inwardly at intervals in accordance with shape of said cowl, a base portion forming a support for the casing, said base consisting of members extending between and secured to the lower edges of the plates, said members having inwardly in-

clined upper walls extending upwardly to the lower edges of the ports in the tubular member, a top portion consisting of members extending horizontally and secured to the top portions of said plates, said members having inwardly inclined lower walls extending upwardly to the upper edges of the ports in the tubular member, said members of base and top portion providing enlarged openings at outer side of said casing substantially equal to the height of said casing, said openings being so constructed that a depending angle of said top portion is in registry vertically with the lower edge of said ports, thereby forming a shield against direct horizontal flow of air into said ports, said vertical division plates being arranged within said casing together with an insertable deflector means in said tubular member, comprising a pair of spring loaded plates secured to each other medially with ends curved outwardly and positioned in registry with said ports, for intercepting air currents from any angle and inducing an accelerated draft upward in said flue by entry of air through said ports as directed upwardly by said openings; said cap from its apex extending downwardly and outwardly to overhang said tubular member and having supports to maintain same in spaced relation to said tubular member, and fastening means for demountably securing same and said casing to said tubular member.

2. A sheet metal cowl comprising a demountable casing constructed to closely fit over the top portion of a steel stack, a demountable cap dimensioned to fit over said casing, said casing having a flanged portion extending upwardly intermediate said stack and said cap and holes in registry through said casing, cap and stack with a plurality of fasteners securing said casing and cap to said stack, said stack being provided with a plurality of ports; said demountable casing consisting of a plurality of vertical division plates positioned radially at intervals, a base portion consisting of members extending between and secured to the lower edges of the plates, said members having inwardly inclined upper walls extending upwardly to the lower edge of the ports in the stack, a top portion consisting of members extending horizontally and secured to the top portions of said plates, said members having inwardly inclined lower walls extending upwardly to the upper edges of the ports in the stack, but having also outwardly inclined lower walls extending upwardly to the top of the casing, providing openings at outer side of casing substantially equal to the height of the casing and forming a depending angle in registry vertically with the lower edge of said ports, thereby forming a shield against conflicting direct horizontal flow of air into said ports, said vertical division plates being arranged within said casing together with an insertable deflector formed of a joined pair of spring loaded outwardly arched plates in said stack, for intercepting an impinging airflow from any angle and by said inwardly inclined walls of casing directed upwardly to create a suction in said stack; said cap having supports to maintain same in spaced relation to top of said stack, providing openings for transverse air currents and having a downward sloping overhang of perimeter of said stack, whereby down draft air currents are deflected and elements of weather are kept out.

3. A cowl comprising a tubular member, an insertable deflector in said tubular member, a demountable casing closely fitting over the top por-

tion of said tubular member, a demountable cap fitting over said tubular member and a restricted portion of said casing; said tubular member being adapted to fit within the upper portion of a flue and having outwardly extending serrations around its bottom perimeter adapted for trimming to closely fit said flue and rest on the upper edge of the lining thereof, a plurality of ports to allow flow of air into said tubular member at a determined height above said flue; said insertable deflector being formed of a pair of outwardly arched plates medially joined and tensed by conforming spring members, said plates providing a barrier of air flow between respective ports by insertion of deflector in line with said ports; said demountable casing consisting of a plurality of vertical division plates extending inwardly at intervals in accordance with shape of said cowl, a base portion forming a support for the casing, said base consisting of members extending between and secured to the lower edges of the plates, said members having inwardly inclined upper walls extending upwardly to the lower edges of the ports in the tubular member, a top portion consisting of members extending horizontally and secured to the top portions of said plates, said members having inwardly inclined lower walls extending upwardly to the upper edges of the ports in the tubular member, said members of base and top portion providing air passages of increased height at outer side of casing substantially equal to the height of said casing, said passages being so constructed that a depending angle of said top portion is in registry vertically with the lower edge of said ports, thereby forming a shield against direct horizontal flow of air into said ports, the arrangement of said division plates together with said deflector in said tubular member intercepting air currents from any angle, which at the same time are deflected upwardly by said air passages creating a suction in said stack, said demountable casing having a cross-sectional construction through a side thereof and an arrangement of vertical division plates whereby it is adaptable to round and straight sided shapes and combinations of same; said demountable cap sloping downwardly from its apex and having supports to maintain same in spaced relation to said tubular member providing openings for transverse air currents, and having fastening means for demountably securing same to said tubular member.

4. A cowl comprising a tubular member, an insertable deflector in said tubular member, a demountable casing closely fitting over the top portion of said tubular member, a demountable cap engaging top of both said tubular member and said casing; said tubular member being adapted to fit within the upper portion of a flue, having means for adjustment to closely fit said flue and having a plurality of ports to allow flow of air into said tubular member above said flue; said insertable deflector being formed of a pair of outwardly arched plates medially joined and tensed by conforming spring members, said plates providing a barrier of air flow between respective ports by insertion of deflector in line with said ports; said demountable casing consisting of a plurality of vertical division plates extending inwardly at intervals in accordance with shape of said cowl, a base portion forming a support for the casing, said base consisting of members extending between and secured to the lower edges of the plates, said members having inwardly inclined upper walls extending up-

wardly to the lower edges of the ports in the tubular member, a top portion consisting of members extending horizontally and secured to the top portions of said plates, said members having inwardly inclined lower walls extending upwardly to the upper edges of the ports in the tubular member, said members of base and top portion providing enlarged openings at outer side of said casing substantially equal to the height of said casing, said openings being so constructed that a depending angle of said top portion is in registry vertically with the lower edge of said ports, thereby forming a shield against direct horizontal flow of air into said ports, said vertical division plates and said deflector intercepting air currents from any angle, said deflector and said depending angle of openings at the same time preventing conflict of any air currents and which are directed upwardly by inclined walls of openings, thereby producing an upward suction and an accelerated draft in the flue; said cap from its apex extending downwardly and outwardly to overhang said tubular member and having supports to maintain same in spaced relation to said tubular member, and fastening means for demountably securing same and said casing to said tubular member, whereby due to such assembly

of parts the mounting and fitting of said cowl to a chimney is greatly facilitated, and also said cap may be readily demounted permitting removal of said deflector for inspection and cleaning of the chimney flue.
